KNITTING NEEDLE

Marcel Vitoux, Paris, France, assignor to American Vitos Company, Inc., New York, N. Y., a corporation of New York

Application March 29, 1947, Serial No. 738,152
In France April 11, 1940

7 Claims. (Cl. 66—117)

1

This invention relates to knitting needles and more particularly to mending needles provided with a pivoted blade.

Needles of this kind are known, and among these needles are such in which the movement of opening of the blade to effect the formation of the mesh, combined with the longitudinal displacement of the needle, is caused by the action of the upper or lower thread of the preceding mesh on an integral component part of the blade or on a driving element which is distinct from the blade.

The difficulties met in the operation of the present day needles of this type are due, primarily to the lack of means for properly guiding and timing the co-operative engagement to the thread or threads of the mesh with respect to certain parts of the blade during its closing movement for bringing said threads towards the hook of the needle. In prior art constructions there is no continuance guidance of the blade by the upper thread or a continuous co-action between the threads and the blade which would tend to keep the upper strand in the hollow space of the blade.

It is, therefore, an object of the present invention to provide a construction which will overcome these difficulties.

Another object is to so form the body of the needle just prior to the closing movement of the blade, that the thread will be positively guided to the spot where said thread co-operatively engages the operating portion of the blade for the closing of said blade.

Another object is to produce a device of the character described in which the maximum simplicity of construction and operation is secured.

Other objects and advantages will appear as the nature of the improvements is better understood, and the co-relation of parts herein fully described, and illustrated in the accompanying drawings, wherein similar reference characters are used to denote corresponding parts throughout the several views, and then finally pointed out and specifically defined and indicated in the appended claims.

The disclosure made the basis of exemplifying the present inventive concept suggests a practical embodiment thereof but the invention is not to be restricted to the exact details of this disclosure and the latter, therefore, is to be understood from an illustrative, rather than a restrictive standpoint.

In carrying out a form of the invention, it was found advantageous to provide a needle with a

2

pivotal mounted blade which is actuated for closing by the lower strand of the mesh on a projecting part of the blade, below the pivot thread as viewed in the drawings, the said lower strand being in contact with an inclined surface of the needle which is also provided with another inclined surface on the upper side thereof with which the upper strand of the mesh is in contact. The lower incline is so arranged with respect to the projecting part of the needle, that at a predetermined period, the lower strand imparts a powerful impulse to the blade in closing direction. The closing movement of the blade is then completed by the upper strand which engages a slot in the upper side of the blade and draws same down until it contacts the hook end of the needle. Furthermore, the invention provides a construction where the blade, particularly during the time in which it cooperates positively with the upper thread of the mesh, is in absolute or sliding positive connection with this strand; likewise, the ultimate action of the lower strand of the mesh on the blade takes place in such a manner that it always occurs according to a definite law, regardless of the initial position of the mesh, which position evidently may vary.

The positive connection between the blade and upper thread of a mesh can be obtained to advantage by means of the above-mentioned slot whose width is only slightly larger than that of the thread; the direction of the slot forms a relatively slight angle with the line joining the pivot of the blade to the nose formed by the said slot.

The guidance of the displacement of the lower thread of a mesh before and during its action on the corresponding part of the blade is preferably obtained by forming between the body of the needle and the blade an angle into which the lower thread is forcibly introduced, before acting on the controlled part of the blade.

The positioning of the upper thread in place before it enters the said slot is preferably obtained by forming between the upper side of the needle body and the side of the blade which constitutes an extension of said slot, a recess where the strand is located before entering the slot.

This positive positioning of the upper and lower threads is further improved by varying the section of the needle body to facilitate the engagement of the lower and/or upper threads in the angles formed for them between the body of the needle and the two opposite sides of the blade, thereby assuring that the blade cannot open at the wrong time.

The invention will be more understandable

from the following detailed description when taken in connection with the accompanying drawings, wherein—

Figure 1 is a fragmental enlarged view in side elevation of a needle made in accordance with the present invention showing the blade in closed position.

Figure 2 is a similar view but showing the blade in the position where it is first engaged by the mesh threads.

Figure 3 is a similar view showing the position to receive the strong closing impulse by the lower thread, the upper strand being about to enter the slot of the guide.

Figure 4 is a top plan view with the blade in the fully open position and

Figure 5 is a similar view to Figure 1 of a modified form of the invention.

Figure 6 is a section along the line 6—6 of Figure 4.

Referring now to the drawings in detail, the numeral 10 indicates a needle shank having an opening 11 in which there is located a blade 12 pivotally mounted on a pivot pin 13 secured to said needle shank. The needle shank 10 is provided with the usual hook 14 at one end thereof with which the blade cooperates to form the mesh of the article being knitted.

The needle shank 10 has a recess 28 located upon its upper edge which faces the hook 14. The recess 28 includes an inclined edge 32, a straight portion and an inclined edge 22, which extends in the opposite direction to the edge 32.

The opposite lower edge of the needle shank 10 has an inclined edge 21 which extends in the same direction as the inclined edge 22, and which is located substantially below the inclined edge 22. However, the inclined edge 21 is considerably shorter than the inclined edge 22.

The form of the blade 12 is clearly apparent from Figures 1 and 2. The blade has an edge 27 located fairly close to the pivot 13, and forming an obtuse angle with the edge 26, constituting a continuation of the edge 27. The edge 26 extends up to the tip of the tail portion 25 of the blade 12. The upper edge of the blade consists of a round portion 24 and a recess or groove 15 which is somewhat wider than the thread 20 adapted to be received in the groove 15. The groove 15 terminates in a nose 16 which cooperates with the hook 14 of the needle shank.

In the drawings the strand engaging the lower edge of the needle shank is designated by the numeral 18, while, as already stated, the strand 20 engages the upper edge of the needle shank.

The blade 12 is of such shape that in the closing position of the needle shank, shown in Figure 1, the nose 16 will contact the hook 14 of the needle shank and thus close the space 17 enclosed by the hook.

On the other hand, in the fully opened position of the blade 12, which is shown in Figure 2, a portion of the blade, which is designated by the numeral 19 in Figures 2 and 3, projects below the lower edge of the needle shank 10. In the fully open position shown in Figure 2 the entire edge 27 and a little portion of the edge 25 of the blade project below the lower edge of the needle shank 10 so that the edge 25 of the blade 12 and the edge 21 of the needle shank form a V-shaped recess within which the thread 18 may be located.

In the partially closed position, shown in Figure 3, it is the edge 27 of the blade 12 which forms a V-shaped recess for the thread 18 with

the inclined portion 21 of the lower edge of the needle shank.

It is apparent from Figure 2 of the drawings that a similar V-shaped recess for the thread 20 is formed by the straight edge 23 of the blade 12 and the inclined edge portion 22.

The needle operates as follows:

When the needle is in the position of maximum opening, the lower strand 18 of the mesh is about to make contact with the side 27 of the blade, while the upper strand 20 is forcibly placed in the recess 28. This theoretical position does not necessarily occur in actual practice; nevertheless, the recess 28 provides that the mesh will be located in the zone of the recess limited by the inclines 22 and 24.

In normal operation the position generally occupied by the mesh is closely related to the position shown in Fig. 2 which corresponds to the start of the operation of forming the mesh. In a subsequent position, the lower thread 18 tends to engage the angle formed by the inclined edges 21 and 26 (Fig. 3), while the strand 20 occupies the recess formed by the inclined edge 22 and the front side 23 of the tail 25. In this position and during the continuation of the upward movement of the needle 10, the lower strand 18 causes the positive opening of the blade by bearing on the lower projection formed by the bend of the blade, and this action proceeds until the upper strand 20 which is located in the angle between the blade and the body engages the slot 15 whose width is only slightly greater than the diameter of the thread of the knitted goods.

From this moment on, the upper strand 20 forms with the blade a positive or sliding connection so that the blade in its lowering movement is guided towards the hook 5 with the thread subsequently passing over the hook to get below the needle in order to form the knitting in the known manner.

It will readily be understood from the foregoing and from an inspection of the drawings that the arrangement described produces positive guiding means of the mesh strands on the body of the needle so as to definitely lead these strands to the desired points for cooperating with the blade. Specifically the upper inclined surface 22 brakes the upper thread 20 which is retarded as it slides up the incline, whereas, on the contrary, the lower thread 18 definitely and suddenly falls off the straight part of the needle into a recess formed at the intersection of the inclined surface 21 and blade projection 19.

This sudden contact results in a forceful impulse upon the needle to overcome its inertia and start its closing movement which is completed by the upper thread 20 acting against the nose 16. The upper thread is urged upwardly along the braking surface 22 by the edge 23 of the blade 12 until it is brought into position adjacent the nose 16 as shown in Figure 3.

It will be seen that, according to the invention, the movement of the blade on its entire travel is controlled either by the lower or the upper strand and that the action of the strands on the corresponding parts of the blade always starts at an exact place determined by the angles formed, on the one hand, by the inclined edges 21 and 26, and 22 and 23, with the movement of the blade then following precisely that of the mesh even during abnormal variations of the movement of the latter.

The result is a much more positive operation

of the blade, any errors being practically impossible.

It may be noted that the bent form of the blade and the distribution of the masses of the latter are such that in the opening position they tend to maintain the blade in this position, thereby preventing any opening of the latter at the wrong time. Under these conditions the opening of the blade can take place only by the positive control of the strands 18 and 20 of the mesh.

Stopping the blade in the position of maximum opening may be obtained with greater certainty by making use of braking means as, for instance, the magnetization of the body of the needle or of the blade. This result can also be obtained by providing a spring 29 (Fig. 4) mounted laterally on the body of the needle, the bending of this body taking place in a notch 30 provided therein; the end of the tail 25 then preferably presents a flat piece 31 which facilitates the engagement of the blade with the spring.

It is to be understood that the above embodiment is not given by way of limitation as numerous modifications and variations may be had without departing from the scope of the present invention, one such modification being shown in Figure 5. In this form of the invention, the blade 12a presents a perfectly straight edge at the bottom thereof and is minus the inclined surfaces which produce the projection 19 above described, the said straight edge and the lower incline 9 of the needle 10a producing a nook 8 for the lower thread to act against and actuate the blade 12a for closing movement. In all other respects the construction of this form is substantially the same as that shown in Figures 1 to 4.

What is claimed is:

1. In a knitting needle having a needle shank, a hook at one end of said shank and a thread-operated blade pivoted upon said needle shank for cooperation with said hook in the formation of a knitted mesh fabric, a projection on said blade extending below said needle shank in the open position of the blade and forming a thread engaging edge on the blade for initiating a pivotal closing movement of the blade towards the hook when engaged by said thread, and an inclined edge on the lower side of the needle shank commencing in advance of the projection on the blade in relation to the movement of said thread and intersecting same to form a recess in which said thread engages and from whence it is guided to impart a forceful impulse to the blade at a predetermined point of its travel.

2. In a knitting needle having a needle shank, a hook at one end of said shank and a thread-operated swingable blade pivoted on said shank for cooperation with said hook in the formation of a knitted mesh fabric pivotally, a projection on said blade extending below said needle shank in the open position of said blade and forming a contacting surface for the lower thread of the mesh for initiating a pivotal closing movement of the blade towards the hook when engaged by said lower thread, an inclined edge on the lower side

of the needle commencing in advance of the projection on the blade in relation to the movement of the thread and intersecting the blade to form a recess in which said thread engages and from whence it is guided to impart a forceful impulse to the blade at a pre-determined point of its travel, the said blade being formed with a slot extending from its upper edge, a nose formed on the blade by said slot, and an inclined edge on the upper side of the needle along which the upper thread of the mesh is guided.

3. A knitting needle according to claim 1, wherein the inclinations of said edges of the blade and the needle and their relative positions are such that the impact of the lower strand of the mesh on the blade is independent of the initial position of the mesh.

4. A knitting needle according to claim 2, wherein the slot of said blade is slightly wider than the diameter of said thread.

5. A knitting needle according to claim 2 comprising a pivot carried by said needle shank and carrying said blade, wherein the slot of said blade forms a comparatively small angle with a line connecting said pivot with said nose.

6. In a knitting needle having a needle shank, a hook at one end of said shank and a thread-operated blade pivoted upon said needle shank for cooperation with said hook in the formation of a knitted mesh fabric, said blade comprising an effective thread-engaging edge for initiating a pivotal closing movement of the blade toward said hook when said edge is engaged by said thread, and said needle shank comprising an inclined edge located partly in advance of the said thread-engaging edge on the blade in relation to the movement of said thread in the open position of said blade for positively guiding said thread on the blade.

40 7. In a knitting needle having a needle shank, a hook at one end of said shank and a thread-operated blade pivoted upon said needle shank for cooperation with said hook in the formation of a knitted mesh fabric, said blade comprising an

45 effective thread-engaging edge for initiating a pivotal closing movement of the blade toward said hook when said edge is engaged by said thread, and said needle shank comprising edges forming recesses located on opposite sides of the needle

50 shank in advance of said thread-engaging edge on the blade in relation to the movement of said thread in the open position of said blade for positively guiding said thread on the blade.
